UNITED STATES PATENT OFFICE.

EDITH SIEGMUND, OF SAN JUAN, PORTO RICO.

DESIGN FOR A DRESS.

Application filed January 14, 1925. Serial No. 12,045. Term of patent 14 years.

To all whom it may concern:

Be it known that I, EDITH SIEGMUND, a citizen of the United States, residing at San Juan, Porto Rico, have invented a new, original, and ornamental Design for Dress, of which the following is a specification, reference being had to the accompanying drawing, forming part thereof, wherein the dress is distinguished by means of two spaced ornamental rectangular inserts A A, located on opposite sides of the front, a centrally-disposed ornamental series B of vertical lines of openwork extending downwardly from the neck opening and between

said inserts, and an ornamental series C of tucks located on each side of the neck-opening.

Figure 1 is a front view of a dress showing my new design.

Figure 2 is an enlarged fragmentary view showing part of the ornamental series B of open-work and a part of one series C of tucks.

I claim:

The ornamental design for a dress, as shown and described.

EDITH SIEGMUND.
